UNITED STATES PATENT OFFICE

ALBERT KELVIN SMITH, OF MIDLAND, MICHIGAN, ASSIGNOR TO THE DOW CHEMICAL COMPANY, OF MIDLAND, MICHIGAN, A CORPORATION OF MICHIGAN

APPARATUS FOR DEHUMIDIFYING AIR, ETC.

Application filed August 26, 1926. Serial No. 131,802.

This invention relates to the dehumidifying of gases and more particularly the treating of air or other gases by moisture-absorbent agents, and it is among the objects of the 5 invention to provide a construction and procedure for the efficient application of moisture-absorbing materials such as calcium chloride and the like, in such use. Other objects and advantages will appear as the 10 description proceeds.

To the accomplishment of the foregoing and related ends, the invention, then, consists of the features hereinafter fully described, and particularly pointed out in the 15 claims, the annexed drawing and the following description setting forth but a few of the various ways in which the principle of the invention may be employed.

In said annexed drawings:—

20 Fig. 1 and Fig. 1A together shown in vertical section one form of embodiment of my invention; Fig. 2 is a vertical sectional view of a modification; Fig. 3 is an enlarged transverse section taken on a plane indicated by the line III—III, Fig. 2; and Fig. 4 is a vertical sectional view showing another modification.

25 In its general aspects, the invention contemplates the provision of a moisture-absorbing agent in such arrangement as to allow progressive supply of replenishing charges, and preferably counter-currently to the flow 30 of gas treated.

35 A container 1, usually of greater length than diameter, has an inlet 2 and an outlet 3 for a gas to be treated, and removable heads 4 and 5, the latter of which may be of a simple screw-cap type, and the former preferably held in a manner to allow quick removal 40 as for instance by bolts 6. Extending through the head 4 is a stem 7 which is arranged for longitudinal movement, as for instance by being screw-threaded and having a coacting nut 8 with suitable means for turning, conveniently a hand-wheel 9. The nut 8 is preferably journaled in a yoke 10 upon the head or capable of being held in fixed relation thereto. The stem 7 carries a plunger 11 and in order to allow passage of gas, this 45 may be perforated and it is further desirable

to apply a facing thereto of wire mesh material 12, the plunger and facing being held to the stem by a nut or the like 13. Near the lower end of the casing and above the gas inlet is a grating 14 which may likewise have 55 a facing of wire mesh material. A drain pipe 15 with control valve 16 is applied at the lower end.

In use, the device is filled with calcium chloride or the like, and gas being admitted at 60 inlet 2 passes up through the moisture-absorbing mass and discharges at outlet 3 being taken off through suitable containers as desired. As the moisture-absorbent material takes up proportionally more moisture at the 65 inlet end, it begins to deliquesce and soften and flow down into the space below from which it may be drawn off by valve 16. In order to make up for the portion of the moisture-absorbing material which softens from 70 the moisture take-up and flows down from the zone of contact, replenishing charges are supplied from time to time. This is accomplished by stopping the gas flow, and forcing the column of moisture-absorbing material down 75 again against the lower grating 14, a heating agent as steam having been admitted into the jacket 17 surrounding the container. The heating agent softens the moisture-absorbing material contiguous to the wall of the 80 container and thus loosens the column so that upon turning the hand-wheel 9, stem 7 and its plunger can be thrust down, thus pushing the column of calcium chloride again 85 into compact position against the lower grating. The yoke 10, head 4 and plunger 11 are now removed, the screw stem and plunger having preferably been run up to facilitate this, and a charge of calcium chloride is filled into the casing to bring the bulk up again to 90 original proportions. The plunger and head 4 are now replaced and the plunger may be tightened down to compact the mass conveniently. In this manner by successively pushing the column of moisture-absorbing 95 material down as it is dissolved away at the gas inlet end, replenishing charges may be added as needed to maintain the effective mass at about its original proportion.

Instead of applying the moisture-absorbing 100

material in the manner described, in some cases I contemplate the use of a stack of trays 18 in the casing 1, each tray containing the moisture-absorbent material, such as calcium 5 chloride. The trays are originally placed so as to fill the space in the container, and as the material in the trays at the gas inlet end liquefies and runs out into the space below, the empty trays may be withdrawn, one or more 10 as the case may be, through the swing door 19 just above the grating 14. New trays to correspond at the same time may also be introduced through a door 20 at the gas outlet end. These doors 19 and 20 may be conveniently 15 mounted on a hinge 21 at one side and have a take-up swing bolt 22 at the other side by which they may be drawn up tightly against the casing. As in the foregoing form, any adherence of the calcium chloride to the con- 20 tainer walls may be overcome to allow movement of the column of trays, by passing steam into the jacket 17, but with this form of device resort to heating is not ordinarily required, and the jacket may be omitted.

25 For very humid gases the deliquescent salt flowing down into the space at the gas inlet end may be made to furnish still further service if a pervious filling 23 be provided, such for instance as stone, coke, Raschig rings, 30 metallic screen, or excelsior, etc. This allows of a good surface exposure of the fluid moisture-absorbent material and at the same time sufficient passageway for the gas is allowed.

In order to quickly cool the mass of calcium 35 chloride or the like after steam has been applied to the jacket 17, it is generally desirable to flood the jacket with cold water.

Other modes of applying the principle of my invention may be employed, change being 40 made as regards the features described, provided the steps or elements stated in any of the following claims or the equivalent of such stated steps or elements be used.

I therefore particularly point out and dis- 45 tinctly claim as my invention:—

1. In an apparatus for dehumidifying gases, the combination of an elongated casing having an inlet for a gas near one end and an outlet near the other end, a readily 50 removable cover at the gas outlet end, means for progressing charges of solid moisture-absorbent material toward the gas inlet end of the casing, and pervious means for exposing a solution of moisture-absorbent material 55 to the gas.

2. In an apparatus for dehumidifying gases, the combination of an elongated casing having an inlet for the gas near one end and an outlet near the other end, a readily re- 60 movable cover at the gas outlet end, means for progressing charges of a moisture-absorb- ing material toward the gas inlet end of the casing, a grating, and a pervious filling be- 65 tween said grating and the gas inlet.

65 3. In an apparatus for dehumidifying

gases, the combination of an elongated casing having an inlet for a gas near one end and an outlet near the other end, a readily removable cover at the gas outlet end, a stem movable through said cover, a plunger carried by said stem within the casing, a grating, and a pervious filling between said grating and the gas inlet. 70

4. In an apparatus for dehumidifying gases, the combination of an elongated casing 75 having an inlet for gas near one end and an outlet near the other end, a readily removable cover at the gas outlet end, a yoke on said cover, a screw-stem supported by said yoke, a plunger carried by said stem within 80 the container, a grating near the gas inlet end of the container, and means for softening moisture-absorbent material adherent to the casing, a drain below said grating.

Signed by me this 20th day of August, 1926. 85
ALBERT KELVIN SMITH.
